UNITED STATES PATENT OFFICE.

CARL F. HAMM, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR CUTTING SHEET MATERIALS.

1,275,250.

Specification of Letters Patent. Patented Aug. 13, 1918.

Application filed August 13, 1917. Serial No. 186,017.

To all whom it may concern:

Be it known that I, CARL F. HAMM, a citizen of the United States, residing at Beverly, in the county of Essex and State of Massachusetts, have invented certain Improvements in Machines for Cutting Sheet Materials, of which the following description, in connection with the accompanying drawings, is a specification, like reference characters on the drawings indicating like parts in the several figures.

This invention relates to machines for cutting sheet material, and more particularly to a type of machine known as the clicking machine which is used extensively for various purposes such as for dieing out uppers and linings in the manufacture of boots and shoes. An object of the invention is to improve the construction of the controlling mechanism of such machines, to the end that time and expense may be saved in assembling and disassembling the parts of the mechanism, particularly when replacement is necessary on account of breakage.

The general characteristics of a well known machine of the type to which the invention relates are illustrated in United States Letters Patent No. 1,131,686, granted on March 16, 1915 upon an application of H. H. Eaton. The machine shown in this patent comprises a post which is mounted to reciprocate vertically in spaced bearings and carries a presser arm which is moved alternately toward and from a work supporting bed by reciprocatory movement of the post, the presser arm being mounted also to swing laterally about the axis of the post to different positions over the bed. Convenient means for actuating the clutch to cause the operating movement of the presser arm is afforded by a handle which is mounted on the presser arm and is movable vertically relatively to the arm to actuate the clutch, the handle serving also as means whereby the arm may be swung to different positions over the bed. In order to maintain an operative connection between the handle and the clutch in all positions of lateral movement of the presser arm, portions of the mechanism between the handle and the clutch are relatively movable about the axis of the post. In the machine shown in the patent the clutch actuating connections comprise a lever which is pivoted on the frame for oper-

ative movement in a vertical plane and has a ring portion which encircles the post between the presser arm and one of the bearings for the post and is spaced from the post a suitable distance to permit its operative swinging movement; and connecting the starting handle to this lever the machine has means including a ring member also encircling the post and having a bearing on the ring portion of the lever.

A difficulty encountered with the construction above described arises from the fact that in order to remove or replace the starting handle ring which is mounted to turn on the ring portion of the clutch actuating lever, it is necessary to remove the post from its bearings, and consequently breakage of this ring member, which sometimes occurs in the use of the machine, occasions considerable delay and expense. A particular object of this invention, accordingly, is to provide a construction having the advantages of the construction heretofore in use without this attendant disadvantage.

To the above and other ends, a feature of the invention consists in an improved construction of controlling mechanism for machines of the type described, including portions relatively movable about the post in bearing engagement with each other, one or more of said relatively movable portions of the mechanism being so constructed as to permit it to be mounted in operative position or removed from the machine without disturbing the operative relation of other parts of the machine including the post.

The invention will now be more particularly explained with reference to the accompanying drawings, and the novel features of improvement, including certain details of construction and combinations of parts, will be pointed out in the claims.

In the drawings,

Figure 1 is a view in side elevation of the upper portion of a machine in which the invention is embodied;

Fig. 2 is a perspective view on a larger scale of a portion of the connections between the starting handle and the clutch, and

Fig. 3 is a plan view of a portion of the mechanism shown in Fig. 2 detached.

The machine comprises a frame 2 having upper and lower bearings 4 and 6 in which a post 8 is mounted for reciprocatory verti-

cal movement, the post having a presser arm 10 secured thereto between said bearings and movable alternately toward and from a cutting bed 12 through the reciprocating movement of the post. In this manner the presser arm is caused to engage a die on the bed and force it through a sheet of material to cut out a blank. In order to permit the arm to swing to different positions over the bed corresponding to different locations of the die upon the material, the post 8, in the construction shown, is also mounted for turning movement in its bearings 4 and 6. Reciprocating movement of the post 8 is effected by rotation of a shaft, not shown, this shaft being driven in the usual manner through connections including a one-revolution clutch. The connections for actuating the clutch comprise a lever 14 pivoted at 16 on the frame of the machine for movement in a vertical plane, the lever being connected with the clutch at its rear end by means of a rod 18. In order to enable the operator to actuate the clutch readily in any position of the presser arm 10 with respect to the cutting bed, a clutch actuating handle 20 is movable with the arm, the handle being mounted for vertical sliding movement on a spindle 22 on the arm to actuate the clutch and serving also as means whereby the arm may be swung from side to side. In order that the handle 20 may maintain its operative relation to the clutch in all positions of lateral movement of the arm 10, the lever 14 terminates at its forward end in a ring portion which encircles the post 8 and is spaced from the post sufficiently to permit the lever to swing as required without engaging the post; and mounted to turn on the ring portion of the lever as a bearing is a member 24 connected to the handle 20 by means of a rod 26 which has its front end forked to project on opposite sides of the handle between flanges 28. For the purposes of this invention the ring portion of the lever 14, in the illustrative construction shown, comprises two annular parts 30 and 32, the part 30 in the construction shown being integral with the lever, while the part 32 is detachably secured to the part 30 by screws 34 and is grooved to provide an annular bearing 36 for the member 24 which is mounted to turn thereon as shown in Fig. 2. The two parts 30 and 32 thus provide flanges which project on opposite sides of the member 24 to hold it on the bearing when the parts are secured together. The member 24 comprises two side portions 38 which are curved to fit the bearing 36 and terminate at a distance from each other which is less than the diameter of the bearing 36 but no less than the diameter of the post 8. As the presser arm 10 is swung in one direction or the other by means of the handle 20, the member 24, by reason of its connection to the handle, turns on its bearing 36 on the lever 14, and whatever may be the position of the arm 10 with respect to the cutting bed, downward movement of the handle 20 will serve, 70 through the connections including the rod 26 and the member 24, to swing the front end of the lever 14 downwardly and thus to trip the clutch by upward movement of the rod 18. 75

It will be evident from the preceding description that in case it becomes necessary, on account of breakage or for any other reason, to replace the member 24, this member may be detached from the machine simply by removing the screws 34 and lifting the annular bearing member 32 to release the member 24 from the bearing 36, whereupon the opening between the two side portions 38 of the member 24 permits the member to be removed transversely of the post 8. 80 By a reversal of these operations a new member may be mounted in operative position. It will be evident, moreover, that when the parts are in their assembled relation, detachment of the member 24 from its bearing is prevented by reason of the fact that the opening between the two side portions 38 is of a width less than the diameter of the bearing 36 upon which the member is mounted. 85

While the invention is disclosed herein by reference a construction including the detachable bearing ring 32 as well as other specific details, it will be understood that in its broader aspects the invention is not limited to the precise construction shown. 90

Having described the invention, what I claim as new and desire to secure by Letters Patent of the United States is: 95

1. In a machine of the class described, the combination with a post and a presser member mounted thereon and movable laterally about the axis of the post, of controlling mechanism comprising a handle movable laterally with the presser member, and connections to said handle for controlling the operation of the machine including parts relatively movable about the axis of the post in bearing engagement with each other, said parts being constructed and arranged for relative assembling or disassembling movement thereof transversely of the post while the post remains in operative position. 100
2. In a machine of the class described, the combination with a post and a presser member mounted thereon and movable laterally about the axis of the post, of clutch actuating mechanism comprising a handle movable laterally with the presser member, and connections to said handle for controlling the operation of the machine including parts relatively movable about the axis of the post and having portions curved around the post in bearing engagement with each 110
3. In a machine of the class described, the combination with a post and a presser member mounted thereon and movable laterally about the axis of the post, of controlling mechanism comprising a handle movable laterally with the presser member, and connections to said handle for controlling the operation of the machine including parts relatively movable about the axis of the post in bearing engagement with each other, said parts being constructed and arranged for relative assembling or disassembling movement thereof transversely of the post while the post remains in operative position. 115
4. In a machine of the class described, the combination with a post and a presser member mounted thereon and movable laterally about the axis of the post, of clutch actuating mechanism comprising a handle movable laterally with the presser member, and connections to said handle for controlling the operation of the machine including parts relatively movable about the axis of the post and having portions curved around the post in bearing engagement with each 120
5. In a machine of the class described, the combination with a post and a presser member mounted thereon and movable laterally about the axis of the post, of controlling mechanism comprising a handle movable laterally with the presser member, and connections to said handle for controlling the operation of the machine including parts relatively movable about the axis of the post in bearing engagement with each other, said parts being constructed and arranged for relative assembling or disassembling movement thereof transversely of the post while the post remains in operative position. 125
6. In a machine of the class described, the combination with a post and a presser member mounted thereon and movable laterally about the axis of the post, of clutch actuating mechanism comprising a handle movable laterally with the presser member, and connections to said handle for controlling the operation of the machine including parts relatively movable about the axis of the post and having portions curved around the post in bearing engagement with each 130

other, one of said curved portions having an opening in one side thereof of a width no less than the diameter of the post to permit it to be removed from the machine while 5 the post remains in operative position.

3. In a machine of the class described, the combination with a post and a presser member mounted thereon and movable laterally about the axis of the post, of controlling 10 mechanism comprising a handle movable laterally with the presser member, and connections to said handle for controlling the operation of the machine including a part provided with a bearing curved about the 15 post and a member mounted to turn on said bearing, said last named member having two side portions partially embracing said bearing and terminating at a distance from each other less than the diameter of the 20 bearing but no less than the diameter of the post.

4. In a machine of the class described, the combination with a post and a presser member mounted thereon and movable about the 25 axis of the post, of clutch actuating mechanism comprising a controlling member movable laterally with the presser member, and connections between said controlling member and the clutch including a lever having 30 a ring portion encircling the post and a part mounted to turn on said ring portion as a bearing, said part having two side portions partially embracing said bearing and terminating at a distance from each other 35 less than the diameter of the bearing but no less than the diameter of the post.

5. In a machine of the class described, the combination with a frame having spaced 40 bearings, a post mounted for reciprocatory movement in said bearings, and a presser member mounted on the post between said bearings for laterally swinging movement about the axis of the post, of starting means comprising a lever having at one end a ring 45 portion loosely encircling said post between the presser member and one of said bearings, a handle mounted to swing with said presser member and also to move in directions transverse to the path of its swinging 50 movement, and means connecting said handle to the lever comprising an operating member mounted to turn on said ring portion of the lever, said parts being so constructed and arranged as to permit said operating member to be removed from the machine or mounted in operative position with- 55

out disturbing the relation of said post and its bearings.

6. In a machine of the class described, the combination with a post and a presser member mounted on the post for laterally swinging movement, of starting means comprising a lever having at one end a ring portion loosely encircling the post and constructed to provide an annular bearing, a 60 handle mounted to swing with said presser member and also to move in directions transverse to the path of its swinging movement, and means connecting said handle to the lever comprising an operating member 65 mounted to turn on said ring portion of the lever, said operating member having two side portions partially embracing said bearing and terminating at a distance from each other no less than the diameter of said post 70 to permit the member to be positioned in or out of its working relation to the axis of said ring portion by a movement transversely of the post.

7. In a machine of the class described, the combination with a post and a presser member mounted on the post for laterally swinging movement, of starting means comprising a lever having at one end a ring portion loosely encircling the post, said ring portion 80 comprising two annular parts detachably secured together and coöperating to provide a circular bearing with a flange at each side of said bearing, a handle mounted to swing with the presser member and also to move 85 in directions transverse to the path of its swinging movement, and means connecting said handle to the lever comprising an operating member mounted to turn on said ring portion of the lever, said operating member having two side portions partially 90 embracing said bearing between said flanges and terminating at a distance from each other less than the diameter of said bearing but no less than the diameter of the post. 95

8. In a machine of the class described, a post 8, bearings 4 and 6 in which the post is mounted, a ring 30, 32 encircling the post between said bearings and providing a bearing 36, and a member 24 mounted on said bearing 36 and including two side portions 38 terminating at a distance from each other less than the diameter of said bearing but no less than the diameter of the post. 100

In testimony whereof I have signed my 110 name to this specification.

CARL F. HAMM.
